F. W. HIRST

FLOW REGULATOR

Filed June 12, 1926

UNITED STATES PATENT OFFICE.

FREDERICK W. HIRST, OF EWING TOWNSHIP, MERCER COUNTY, NEW JERSEY.

FLOW REGULATOR.

Application filed June 12, 1926. Serial No. 115,511.

The invention relates to a flow regulator adapted to control or regulate the flow, to settling tanks of any suitable construction, of waste liquids containing solid materials 5 of any variety of composition that may constitute the waste products of an industrial plant when the recovery or separation of such solids from its liquid carrier is desirable or necessary.

10 My improved apparatus is particularly adapted for installation in a wood pulp mill or manufactory in which wood pulp is used as a basic substance for the molding or shaping of a final product.

15 In such plants, the effluent from the molds contains pulp fibres which must be separated out before the said effluent may be discharged either into a sewer or into a navigable stream. The recovery or separation 20 of such fibres is usually accomplished by means of settling tanks, rectangular or conical in vertical cross section, in which the waste material is permitted to settle to the bottom and the liquid drawn off or allowed 25 to overflow continuously at the top. The deposit of solid matter at the bottom of the settling tank can then be periodically removed.

The object of the invention is to provide 30 an apparatus of simple construction to control and regulate the flow of waste liquid to such tanks to make it uniform rather than irregular, as would necessarily be the case if the liquid were passed directly to the 35 settling tanks.

In the accompanying drawings, Fig. 1 is 40 a sectional elevation of an apparatus embodying the invention; Fig. 2 is a section on the line 2—2 of Fig. 1; and Fig. 3 is a section on the line 3—3 of Fig. 2 showing details of the weir.

Referring more particularly to the drawings, the numeral 1 represents a receiving tank adapted to receive the waste liquid 45 from part or all of the plant, depending upon its capacity, and from which it is adapted to flow through a conduit 2 and gate valve 3 to the control tank 4. A pair of weirs 5 provide an overflow outlet from tank 4 into chambers 6 and 7 which connect with pipes 8 and 9 leading to the same or different settling tanks (not shown).

In order to maintain an even rate of flow into the tank 4 and consequently into the 55 settling tank therefrom, valve 3 is positioned

only slightly above the level of weirs 5. The valve may be of any standard construction, but I prefer the type shown in the drawings commonly referred to as a Standard automatic sewer gate, in which the numeral 11 represents the gate, and 12 is an actuating arm pivoted at 13 carrying adjustable weight 14. A link 15 connects arm 12 with lever 16 which is pivoted at 17 to the baffle wall 18. A float 20 is suspended by 60 means of a rigid arm 21 from lever 16 near pivot 17. The large lever ratio, for instance, 1 to 5, of the arms of lever 16 renders the adjustment of valve 3, controlling the flow of liquid into the control tank 4, 65 very sensitive. Float 20 is protected against eddies by a second baffle 22 placed immediately in front of it. A liquid-level gauge 23 is actuated by a second float 24 and may be graduated to read in inches or other suitable units. The weirs 5 are formed with two plates 25 having slots 26 adapted to 70 adjustably receive bolts 27 and carrying wing nuts 28 whereby the plates may be secured when they have been moved to their adjusted position. Each weir is provided with knife edges 30, and the notches 31 are of rectangular or other standard cross section to facilitate computation of the flow 75 therethrough.

The valve mechanism as shown and described hereinabove may be used in connection with the regulation of various types of flow and is not limited for use in connection with settling tanks and waste liquids. 80 It may be used, for instance, in connection with a flow tending to enter the regulator tank, such as Fig. 4, irregularly, for instance, at varying rates of speed or varying quantities, or leaving said tank at varying 85 rates of speed or in varying quantities. In other words, my valve mechanism may be employed for accurately maintaining a constant water level; or to maintain such level in any open receptacle when the discharge 90 from the same is in variable quantities and at different periods of time, as long as the supply going through the valve is adequate 95 to support the float at the desired level.

I claim:

A flow regulator comprising a receiving tank to which liquid is irregularly admitted; a control tank; a conduit connecting said tanks; means for maintaining the liquid level in said control tank substantially con- 105 110

stant, comprising a gate controlling the flow through said conduit, a pivoted actuating arm for said gate, a pair of spaced baffles in said control tank, a lever pivoted at one end to one of said baffles and connected at its other end to said actuating arm, and a float in said control tank between said baffles and

connected to said lever at a short distance from its pivoted end; and a weir normally positioned slightly below the level of said valve, forming an outlet from said control tank.

FREDERICK W. HIRST.
